UNITED STATES PATENT OFFICE.

CHARLES S. HOOPER AND ROBERT C. STEVENS, OF ERIE, PENNSYLVANIA.

STEAM-SUPERHEATER.

1,125,099.

Specification of Letters Patent. Patented Jan. 19, 1915.

Application filed October 27, 1913. Serial No. 797,552.

To all whom it may concern:

Be it known that we, CHARLES S. HOOPER and ROBERT C. STEVENS, citizens of the United States, residing at Erie, in the county of Erie and State of Pennsylvania, have invented certain new and useful Improvements in Steam-Superheaters; and we do hereby declare the following to be a full, clear, and exact description of the invention, such as will enable others skilled in the art to which it appertains to make and use the same, reference being had to the accompanying drawings, and to the letters of reference marked thereon, forming part of this specification.

This invention relates to steam superheaters of the type in which the steam is received in a drum to which return bend heating-tubes are secured.

The object of our invention is to produce a steam super-heater of this type in which there is provided means by the operation of which the heating-tubes are caused to operate as a series of groups of tubes, so that steam on being received into the drum will enter and pass through one group of tubes, and then enter and pass through another group of tubes, which operation is repeated as many times as there are divisions of heating tubes into groups.

A further object is to so construct the interior mechanism of the super-heater that it may be readily placed within, and removed from the drum.

The features of our invention are herein-after more particularly pointed out and are illustrated in the accompanying drawings in which:

Figure 1, is a side view in elevation of a steam-super-heater embodying our invention. Fig. 2, is a horizontal central section of the same, through the drum, looking downward. Fig. 3, is a transverse section of the same, on the line $x-x$ in Fig. 2, looking in the direction of the arrow. Fig. 4, is a transverse section of the same on the line $y-y$ in Fig. 2, looking in the direction of the arrow. Fig. 5, is a transverse section of the same on the line $z-z$ in Fig. 2, looking in the direction of the arrow.

In these drawings, A, indicates a drum, and $a-a$, indicates metal rings secured in the ends thereof, to which the drum-heads B and B', are secured in the usual manner. One of these heads B, is provided with an opening b , and the other with an opening b' ,

with which steam pipe connections C, and C', communicate. In the shell of the drum A, are secured return-bend U-shaped heating tubes D, D', and D'', in such a manner that their ends are in rows longitudinally of the axis of the drum A, and the two ends of each tube are located on lines at right angles thereto.

Within the drum A, we place an open face box-like member E, which covers the exit ends of the tubes D, and the entrance ends of the tubes D', and beside this member E, we place another box-like member E', so, that it will cover the exit ends of the tubes D', and the entrance ends of the tubes D'', and endwise with the member E, and beside the member E', we place another box-like member E'', so that it will cover the exit ends of the tubes D''. From the last E'', of the box-like members, a tubular duct F, leads to the opening b' , in the head B'. While we show the exit opening b' , to be located in the head B', we do, when it is desirable, place the exit b' , in the shell of the drum, and likewise opening b , for the admission of steam may be placed in the shell of the drum A, when desired.

To secure the members E E', and E'', in their places over the ends of the tubes as above described, straps G, are placed over them, the ends of said straps being secured in a removable manner to the shell of the drum, preferably by means of tap-bolts g, secured in the shell of the drum A, and placing on said tap-bolts g, nuts g'. It will be seen from the drawings and the foregoing description that before securing the heads B and B', on the drum A, the members E E', and E'', can be inserted through the rings a, and placed over the tube ends as above described, and the strap G, secured in place thereon, so that the members E E', and E'', will be retained in their proper positions as above described, no matter what the position of the super-heater may be. Owing to the liability of the return-bend tubes becoming damaged, and the necessity of having to remove such damaged tubes and replace them with new tubes, the removability of the members E, E', and E'', is an essential feature of our invention, as otherwise it would be impossible to make such repairs.

In operation, steam is admitted into the drum A, through the opening b , in the head B, so that the drum A, is filled therewith from end to end around the box-like mem-

bers E, E', and E². Owing to the baffling effect of the members E, E', and E², the steam readily enters the uncovered entrance ends of the tubes D, and passes through 5 into the box-like member E, and moves longitudinally therein to and enters the tubes D', and passes therethrough into the box-like member E, and moves longitudinally therein to and enters the tubes D', and 10 passes therethrough into the box-like member E', and moves longitudinally therein to, and enters the tubes D², and passes therethrough into the box-like member E², and moves longitudinally therein to the tubular 15 duct F, which conducts the steam which has passed through the tubes as above described, to the exit opening b'.

It will be observed that in the arrangement of this super-heater, no packing is 20 used between the members E E', and E², and the shell of the drum A, or between the duct F, and the outlet b', but that owing to the fact that these members are completely 25 surrounded by steam at approximately uniform pressure, such packing is unnecessary, and that steam, on entering the drum A, will take the easiest route to travel, which owing to the baffling box-like members E E', and E², is through the tubes D, D', and 30 D², in succession.

It will be observed from the foregoing, that the box-like members E E', and E², while separating the super-heated steam which is passing through the tubes from the 35 saturated steam within the drum A, they also serve as mixing chambers, wherein particles of steam which have passed through each of said tubes D D', and D², are thoroughly inter-mixed before leaving each of 40 said members.

Having thus fully shown and described

the construction and operation of our invention, what we claim as new and desire to secure by Letters-Patent, is:—

1. In a steam super-heater, the combination of a drum to receive steam, a series of return-bend tubes having their ends secured in the shell of said drum, an open-faced box-element longitudinally situated within said drum and inverted over the right hand ends of said return bend tubes, and another open-faced box-member longitudinally situated within said drum beside the first mentioned box-like member, inverted and extending over the left hand ends of said tubes part way from the exit end of said drum toward the entrance end thereof, and a tubular duct leading from the last of said box-like members to the exit opening from said drum, substantially as set forth. 45 50 55

2. In a steam super-heater, the combination of a drum to receive steam, a series of return bend tubes having their ends secured in said drum shell in longitudinal rows, a series of open-faced box-like members inverted over one row of said tube ends, and a less member of said box-members beside, and so arranged as to overlap any two of the first mentioned box-like members and cover all but a few of one end of said return bend tubes, and a duct leading from the last of said box-like members to exit opening of said drum, and means to secure said box-like members in place within said drum, substantially as set forth. 60 65 70 75

In testimony whereof we affix our signatures, in presence of two witnesses.

CHARLES S. HOOPER.
ROBERT C. STEVENS.
